(57) **CLAIM**

The ornamental design for an air cylinder cart frame, as shown and described.

DESCRIPTION

FIG. 1 is a top perspective view an air cylinder cart frame; FIG. 2 is a bottom perspective view of the air cylinder cart frame shown in FIG. 1 from a side opposite that shown in FIG. 1;

FIG. 3 is a front elevation view of the air cylinder cart frame shown in FIG. 1;

FIG. 4 is a rear elevation view of the air cylinder cart frame shown in FIG. 1;

FIG. 5 is a top plan view of the air cylinder cart frame shown in FIG. 1;

FIG. 6 is a bottom view of the air cylinder cart frame shown in FIG. 1;

FIG. 7 is a right side elevation view of the air cylinder cart frame shown in FIG. 1; and,

FIG. 8 is a left side elevation view of the air cylinder cart frame shown in FIG. 1.

The broken lines shown in the figures are for the purpose of illustrating portions of the air cylinder cart frame which form no part of the claimed design.

1 Claim, 7 Drawing Sheets
